Primary Examiner — Mark Goodwin*(74) Attorney, Agent, or Firm* — Wegman, Hessler & Vanderburg(57) **CLAIM**

We claim the ornamental design for a docking station, as shown and described.

DESCRIPTION

FIG. 1 is a top perspective view of a docking station showing our new design;

FIG. 2 is a front view thereof;

FIG. 3 is a rear view thereof;

FIG. 4 is a left side view thereof;

FIG. 5 is a right side view thereof;

FIG. 6 is a top view; and,

FIG. 7 is a bottom view.

The broken lines shown in the drawings are for the purpose of illustrating portions of the article that form no part of the claimed design.
